UNITED STATES PATENT OFFICE.

GEORGE L. BEERS, OF WILKINSBURG, PENNSYLVANIA, ASSIGNOR TO WESTINGHOUSE ELECTRIC & MANUFACTURING COMPANY, A CORPORATION OF PENNSYLVANIA.

SUPERHETERODYNE RADIO SIGNALING SYSTEM.

Application filed February 10, 1925. Serial No. 8,209.

My invention relates to radio receiving systems and particularly to superheterodyne receiving systems.

An object of my invention is to construct 5 a radio receiving system in which provision is made for the prevention of the re-radiation of local oscillations.

Another object of my invention is to provide means for increasing the selectivity of 10 a sensitive radio receiving system.

Another object of my invention is to improve the ratio of signal strength to extraneous noises in a superheterodyne radio receiving system.

Another object of my invention is to provide means for the prevention of the radiation 15 of the frequencies present in a superheterodyne radio receiving apparatus.

Another object of my invention is to provide means for preventing the response of a 20 superheterodyne radio receiving apparatus to undesired signals having frequencies which are heterodyned by harmonics of the oscillation generator frequency.

In the operation of the superheterodyne 25 radio receiving system, it has been found to be exceedingly sensitive and within certain limitations exceedingly selective. It has likewise been found to give a signal strength 30 which, in its ratio to extraneous noises, has been equal to or better than previous apparatus but, as is the case with all radio apparatus, a certain amount of noise has been found to be present.

Also the presence of a local oscillation 35 generator, as a part of the receiving apparatus, has resulted in the radiation of radio frequency energy from the antenna system of the receiver, at the local oscillation frequency. This radiated energy, or the so-called "re-radiated energy", is troublesome to 40 near-by receivers producing objectionable noises, howls and whistles in them.

While the superheterodyne radio receiving 45 system has been found to be among the most selective known, it has not been found possible to construct the system in such way as to avoid absolutely all interfering signals. It has been found that a powerful near-by 50 sending station will force oscillations in the antenna system which may be carried through the amplifier system to the phones or loud speakers. It has also been found that even with the utmost care in construction, 55 an oscillation generator produces more than

one frequency. It produces the fundamental frequency to which it is tuned and also one or more harmonics of that frequency. When the frequency of the generator is set at the proper value to heterodyne a desired signal 60 to the beat frequency for which the apparatus is designed, it is possible that a nearby station may be operating upon a frequency which will heterodyne with the first harmonic of the generator to produce the beat 65 frequency for which the system is designed, thereby causing troublesome interference.

My invention provides a construction which, by the addition of one element, simultaneously increases the selectivity of the system, prevents the re-radiation of the local oscillations and improves the ratio between the strength of received signals and noises 70 from static strays and tube noises.

Other objects and structural details will 75 be apparent from the following description when read in connection with the accompanying drawing, wherein:

Figure 1 is a diagrammatic view of circuits and apparatus embodying a preferred 80 form of my invention; and

Fig. 2 is a diagrammatic view of circuits and apparatus of a modification.

Referring to the drawings, a radio receptor 1, which may preferably be a loop antenna, is connected to an amplifier triode 2. A tuning condenser 3 is connected to the receptor 1 at the points of connection between it and the amplifier tube. A local oscillation generator 4 having an adjustable tuned oscillating circuit 5 is provided. The anode of the triode 2 is connected to an output coil 6 which is inductively associated with the input coil 7 of a heterodyne resolving detector 8. The inductor of the oscillatory circuit 5 is inductively associated with the coil 7. The resolving detector 8 has a coil 9 in its output circuit which is inductively associated with the input coil of an amplifier system 11 which, in turn, is connected to a detector 12 and signal translator 14. The coil 7 is shunted by a tuning condenser 15.

The condensers 3 and 15 are suitably chosen with respect to the antenna 1 and the coil 7, and are such that equal movements of the mechanical portions thereof produce equal changes in the resonant frequencies of the circuits of which they are parts. They are then mechanically connected to a single control and indicating means, whereby the 110

resonant frequencies of the two circuits are kept substantially equal over the tuning range.

- In the embodiment shown in Fig. 1 an additional coil 16 is connected to the terminal of coil 6 and inductively associated therewith in a reverse direction. The second terminal of the coil 16 is connected through a condenser 17 to the grid circuit of the triode 2, 5 constituting a reverse feed-back system of the type disclosed in the patent to Rice, No. 1,334,118, whereby the triode 2 is prevented from having any tendency to go into self-oscillation.
- 15 In the modification shown in Fig. 2, a connection is made from the anode circuit of the triode 2 through a condenser 18 to a midpoint upon the loop 1 substantially as disclosed in my co-pending application, filed 20 February 10, 1925, Serial No. 8,208.

In the operation of my device, the antenna 1 is tuned to the frequency of the desired signals by the adjustment of the condenser 3. Incoming signals are then impressed upon 25 the grid of triode 2. They may be slightly amplified therein and then transferred by way of coils 6 and 7 to the grid of the triode 8. Energy from the oscillator 4 is transferred by way of the resonant circuit 5 to coil 7. The two frequencies produce a beat phenomena which is resolved and detected by the triode 8 to a lower radio frequency and then amplified and detected to audio frequency signals by the amplifiers 11 and detector 12.

In the first embodiment of my invention, just described, the triode 2 is prevented from self-oscillation by the presence of the reverse feed-back obtained by the combination of the 40 coil 16 and condenser 17. In the operation of the system, energy from the local oscillator 4 is impressed upon the coil 7 and some energy is unavoidably impressed upon coil 6, because of its coupling thereto and the production of potential differences therein. Energy is also simultaneously impressed upon the coil 16 which, being wound in reverse direction and closely coupled thereto, causes the development of potential in a reverse 45 phase. The capacitance of condenser 17 is made approximately equal to the inter-electrode capacity of the triode 2 and, therefore, the energy impressed upon the grid of the triode 2 from the coils 6 and 16 consists of two components, which are substantially 50 equal and opposite in phase and are thereby mutually neutralized. In consequence thereof, no local energy is impressed upon, or 55 radiated from, the receptor 1.

60 Simultaneously, the introduction of the second tuned circuit consisting of the coil 7 and the condenser 15, provides an additional filter trap which increases the selectivity of the system to incoming signals. The filter trap is made resonant to the desired signals

and being non-resonant to other frequencies, rejects undesired signals. Likewise, the presence of the two resonant circuits and the presence of the triode 2 attenuates the amplitude of untuned electrical impulses which 70 reach the antenna and they are, therefore, reduced in intensity as compared to the desired signals, thereby improving the ratio between the strength of the signal and the strength of interfering noises. 75

The condensers 3 and 15 may be mechanically interconnected and, therefore, a change of the setting of one changes the setting of the other. These changes being made simultaneously, the two circuits as described are 80 kept simultaneously resonant to the same frequency when a change of the received signal frequency is made.

The embodiment of my invention shown in Fig. 2 operates in a substantially similar 85 manner and obtains similar results to the first described embodiment, with the exception that energy from the local oscillation generator is allowed to pass simultaneously to the inter-electrode capacitance of the triode 90 2 to the grid thereof and simultaneously in reverse phase through half of the loop antenna 1 thereby inducing in the other half thereof currents in reverse phase which are impressed upon the grid of triode 2. The 95 presence of the second described currents impressed from the loop 1 upon the grid of triode 2 neutralizes the currents induced directly through the inter-electrode capacitance and thereby prevents local oscillation 100 of the triode 2 and allows it to respond only to incoming signals.

While I have shown and described but two embodiments of my invention, it is capable 105 of various changes and modifications therefrom without departing from the spirit thereof and it is desired therefore that only such limitations shall be imposed thereon as are indicated in the prior art or in the appended claims. 110

I claim as my invention:

1. In a radio receiving system, a receiving circuit capable of radiating, means associated therewith and including a local source of oscillations for heterodyning an incoming signal to a different frequency, a vacuum-tube device and a circuit network interposed between said local source and said receiving circuit, and connections between said receiving circuit, said vacuum tube and said network such that oscillations from said local source are impressed on the receiving circuit through said network and said vacuum tube in opposing phase relation, whereby said locally generated oscillations are prevented 120 from being radiated by said receiving circuit. 125

2. In a radio receiving system, a receiving circuit capable of radiating, a local source of oscillations for heterodyning an incoming 130

signal to a different frequency, means for deriving an audible signal from said different frequency, a vacuum-tube device and a circuit network interposed between said deriving means and said receiving circuit, said vacuum-tube device and said circuit network together constituting an amplifying filter capable of transmitting a desired signal with minimum attenuation, and presenting larger attenuation to all other frequencies capable of interacting with said local source to produce said different frequency, and connections between said receiving circuit, said vacuum tube and said network such that oscillations from said local source may be impressed on the receiving circuit in opposing phase. ¹⁵

In testimony whereof, I have hereunto subscribed my name this 3rd day of February, 1925.

GEORGE L. BEERS.
